(57) **CLAIM**

The ornamental design for a cable connector, as shown and described.

DESCRIPTION

FIG. 1 is a front perspective view of a cable connector showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof;

FIG. 9 is a partially-exploded rear perspective view thereof; and,

FIG. 10 is an enlarged view of the portion delineated in FIG. 1.

The dashed broken lines in the figures illustrate portions of the cable connector that form no part of the claimed design. The dot-dash broken lines in FIGS. 3, 8, and 9 define the boundary of the claimed design and form no part thereof. The dot-dot-dash broken lines in FIGS. 1 and 10 delineate a portion of the claimed design that is illustrated in an enlarged view and form no part of the claimed design.
